UNITED STATES PATENT OFFICE.

EDWARD G. DOYEN, OF SAN FRANCISCO, CALIFORNIA.

MATTRESS-TUFTING MACHINE.

Application filed January 27, 1921. Serial No. 440,319.

To all whom it may concern:

Be it known that I, EDWARD G. DOYEN, a citizen of the United States, residing at San Francisco, in the county of San Francisco, 5 State of California, have invented a new and useful Mattress-Tufting Machine, of which the following is a specification in such full and clear terms as will enable those skilled in the art to construct and use the same.

This invention relates to a mattress tufting machine and its object is to provide a machine which will be capable of pushing all of the needles for one transverse row of tufting through the mattress at one time, after which the needles are removed and shifted several inches to place another transverse row of tufting.

It will be understood by those skilled in the art that in tufting a mattress a long needle is used, and is pushed through the mattress from one side to the other, whereupon one tuft is inserted under the loop of the string and the needle is then withdrawn and another tuft is then tied against the opposite side of the mattress and the first tuft to prevent the mattress filling from shifting when the mattress is in use.

With the present invention enough needles are used to tuft one complete transverse row at one time, all of the needles being carried by a frame which pushes them through the mattress at one time.

Another object of the invention is to provide a machine which is capable of actually measuring the distance between the transverse rows of tufting, thereby avoiding the awkward appearance caused by the tufting being out of line.

Another object of the invention is to provide means whereby the mattress will be held down during the time the needles are being pushed through it.

Another object of the invention is to arrange the operation so as to prevent the strings used from being pulled out of place during the time the mattress is being worked upon, the strings being cut after the tufts have all been inserted on one side of the mattress.

Other objects of the invention will appear as the description proceeds.

An embodiment of the invention is shown in the drawings in which the same numeral

reference is applied to the same portion 55 throughout, but I am aware there may be modifications thereof.

Figure 1 is a plan view of the complete machine.

Figure 2 is a sectional end view on line 60 2-2 of Fig. 3.

Figure 3 is a side elevation of the complete machine.

Figure 4 is a view of a portion of the mattress and one needle illustrating the manner 65 of tying in the tufts.

The machine comprises four supporting posts 1 to 4 inclusive. These posts are connected together by two side rails 5 and 6 and by two transversely extending side rails 7 70 and 8, which are in turn connected to the posts by means of two braces 9 and 10 at each end.

At the top the posts are connected together by two transverse stringers 11 and 12 75 at one end and stringers 13 and 14 at the other end. These stringers being separated by spacing members 15 and 16 but which spacing members are not as wide as the members which they space.

Extending into the grooves produced between the members 11 and 12 and 13 and 14 are two fixed slats 18 and 19 and seven adjustable slats 20 to 26 inclusive. There are used such number of adjustable slats as is 85 required to produce the proper number of supports for the number of needles used on any given mattress.

Each of the rails 5 and 6 has a longitudinally extending track as shown at 27 and 28, 90 each of the tracks supporting a two wheeled carriage 30, the wheels being indicated at 31 and 32 in dotted lines.

Depending from the carriage 30 are two bars 33 and 34, which are connected by a 95 bottom cross bar 35. The bottom cross bar 35 is connected to the two depending bars 33 and 34 by means of two braces 36 and 37. The depending bars 33 and 34 carry guides 38 and 39 in which a rectangular frame, having the horizontal members 40 and 41 and end members 42 and 43, is vertically slidable.

Each of the depending bars 33 and 34 has a block as indicated at 44 and 45, said block supporting guides 46 and 47 through which 100 105 two slidable bars 48 and 49 move.

The carriage 30 has guides 50 and 51 through which the two bars 48 and 49 pass.

Bolted on the sides of depending bars 33 and 34 are two straps 53 and 54, said straps being provided with a plurality of openings to receive the pivot pins for levers 55 and 56. These levers 55 and 56 are connected to horizontal member 40 of needle frame, by means of two links 57 and 58. At the end of each lever there is a stirrup 59 and 60, for the use of the operator.

10 The slideable bars 48 and 49 carry two cross bars 62 and 63, which are separated from each other far enough to permit the necessary space for the operator to accomplish the tufting when the needles have been pushed through, and said bars hold the mattress down when the entire set of needles is being pushed through it.

15 The slideable bars 48 and 49 are connected to the levers 55 and 56 by links 65 and 66, and both levers 55 and 56 and said links 65 and 66 are provided with a plurality of holes so as to adjust the height of cross bars 62 and 63 to correspond with the thickness of the mattress being tufted, and the length of 25 the bars is arranged so that the needles will just show through, as shown in Fig. 4, when the mattress is pressed down tightly by cross bars 62 and 63.

20 The tufting needles are indicated at 67 and they are carried by adjustable slides 68 on the horizontal member 41. These slides are held in any given adjustment by means of set screws 69. In order to provide for the automatic adjustment of the position of the 30 needles following each tufting operation, the carriages 30 are provided with stiff springs 70 operated by means of knobs 71. These springs engage notches on a steel plate 72, supported by a rail 73 extending between 40 the posts. There is a rail 73 at each side of the machine and a spring 70 for each carriage 30.

45 Each carriage 30 is also connected to a cable 74 which extends around a pulley 75 at one end of the machine, and over a pulley 76 on the ceiling of the room in which the machine is installed, and at its end it is provided with weights 77, so that when the 50 spring is removed from the notches the weights cause the carriage carrying the needles to move to the next position automatically.

The operation of the apparatus is as follows:

55 Assuming the needles to be threaded with a suitable heavy cord or twine, one end of said cord is knotted as indicated at 78, and the operators, one at each side of the machine, press upon the stirrups 59 and 60, causing 60 the needles to press up through the mattress, thereupon a tuft 79 is placed under the loop of string 80; the needles are removed and shifted to another position, whereupon another tuft 81 is inserted in the loop of the 65 string and the operation continues to the

end of the mattress, a ball of cord or twine being used for each needle. When the tufts are all placed on one side of the mattress, it may be turned over and the string cut and other tufts inserted upon the other side at 70 will.

What I claim is as follows, but various modifications may be made in the construction shown in the drawings and above particularly described form, within the purview 75 of my invention:

1. A mattress tufting machine comprising a frame having supports for the mattress, a cross bar extending over the mattress to prevent it from rising, a frame carrying a plurality of needles and with which said cross bar is movable, levers for raising the frame carrying the needles and depressing the bar above the mattress, side rails carried by the first frame, a slideable carriage 80 movable along said side rails to which the needle carrying frame is secured, and a gauge along side the mattress support for spacing the tufts.

2. A mattress tufting machine comprising a frame having a mattress support, said support consisting of a plurality of adjustable slats, a vertically movable frame, a plurality of needles carried by the frame and adjustable thereon to correspond with 95 the openings between the slats for supporting the mattress, a cross bar extending over the mattress to prevent it from rising, and levers for raising the needle carrying frame and depressing the cross bar when the 100 needles are being pushed through the mattress.

3. A mattress tufting machine comprising a frame, a support carried thereby for a mattress, a vertically movable frame, a plurality of needles carried by said frame below the mattress support, a cross bar above the mattress to prevent it from rising when the needles are being pushed through the 105 mattress, a carriage for the support of the needle frame, means to move said carriage longitudinally of the mattress, and a gauge 110 for positioning the needles each time they are to be pushed through the mattress.

4. A mattress tufting machine comprising a frame, a mattress support carried thereby, a carriage movable longitudinally of the mattress supporting frame, a needle carrying frame movable vertically in said carriage, a cross bar extending over the mattress, means to move said cross bar against the mattress, and to push the needles upward through the mattress at the same time, and a gauge on each side of the frame for determining the position of the needles each 115 time they are to be pushed through the mattress.

5. A mattress tufting machine comprising a frame, a support carried thereby for a mattress, a carriage movable longitudinally 120

- of the frame below the mattress support, a vertically movable frame in said carriage, needles carried by said frame, a cross bar extending over the mattress and supported by said carriage, levers for pulling said cross bar into engagement of the mattress, and pulling needles through the mattress at same time, a gauge at the sides of the frame, and springs on the carriage adapted to contact with said gauge to determine the several positions at which the needles are to be pushed through the mattress.
6. A mattress tufting machine comprising a frame having a support for a mattress, a carriage movable longitudinally of the frame below the support for the mattress, a vertically movable frame supported in said carriage, a cross bar extending over the mattress for preventing the mattress from rising, means to move cross bar down into engagement with the mattress and simultaneously pushing the needles through it, means to equally space the positions at which the needles are to be forced through the mat-
- tress, and means to pull the carriages into position after each operation of the needles.
7. A mattress tufting machine comprising a frame, a support for the mattress, a bar extending over the mattress for preventing it from rising, a carriage movable longitudinally of the frame, a plurality of needles, a vertically movable frame carrying said needles and supported by the longitudinally movable carriage, levers extending on opposite sides of the machine for pulling the cross bar down and pushing the needles up through the mattress, gauges at opposite sides of the machine, stops carried by movable carriage for determining the position at which the needles are to be pushed through the mattress, and means to move the carriage longitudinally of the machine after each operation of the needles.
- 10 15 20 25 30 35 40 45

In testimony whereof I have hereunto set my hand this 19th day of January, A. D. 1921.

EDWARD G. DOYEN.
